UNITED STATES PATENT OFFICE.

LOUIS ALEXANDRE CADORET, OF PAWTUCKET, RHODE ISLAND.

BOBBIN RETAINER.

Application filed February 7, 1924. Serial No. 691,243.

To all whom it may concern:

Be it known that I, LOUIS A. CADORET, a citizen of the United States, residing at Pawtucket, in the county of Providence and 5 State of Rhode Island, have invented certain new and useful Improvements in Bobbin Retainers; and I do declare the following to be a full, clear, and exact description of the invention, such as will enable others skilled in the art to which it appertains to make and use the same.

This invention relates to an improved retainer for bobbins of the type used in association with loom shuttles and while it 15 has more specific reference to the type wherein the usual pivoted spindle is eliminated, it is not to be restricted to this species.

Ordinarily, the bobbin retaining clip is rigidly secured to the shuttle at one end of the recess therein and it follows that when the bobbin is in operative position, it is held rigidly. It has been observed that with this form of construction, the thread is permitted to slip and the desired tension thereon is not obtained. This undesirable and loose unwinding of the thread is undoubtedly caused by the shock to which the bobbin is subjected when it is slid in one direction across the loom track, or 25 checked when slid in the other direction, it being well known that the winding of the thread on the bobbin or the like is usually such that one conical layer of such thread or possibly more, may readily slide in one 30 direction from the remainder of the windings but cannot slide in the other direction. Thus, during the operation of the shuttle when the shuttle is driven in one direction by the picker stick, there is a tendency to drive the bobbin out of some of 35 the endmost windings of thread, and when the bobbin is checked on its return movement, the endmost windings of thread have a tendency to leave the other windings by 40 momentum.

Otherwise stated, when the shuttle is driven in one direction across the track by the picker stick, the bobbin and shuttle move instantaneously as a unit. When the 45 other end of the track is reached however, and the impact is received from the opposite picker stick, the bobbin is subjected to a disastrous shock because it is momentarily

inert. This retardation of the movement of the bobbin serves, as before stated, to permit undesirable unwinding of the thread-convolutions.

In view of the foregoing conditions, I propose to provide an improved and novel bobbin retainer which has shock-absorbing means associated therewith to permit slight relative longitudinal movement between the bobbin and shuttle to prevent undue unwinding of the thread such as now occurs.

It is therefore the primary feature of the present invention to provide simple and practical means for absorbing the shock to which the bobbin is subjected.

A secondary, yet a very important feature of the invention, is to provide a retainer of the class described which is such in construction as to accomplish the result above specified, and has the additional function of providing a self-adjusting retainer such as will accommodate various sized bobbins.

Other features and advantages of the invention will become apparent from the following description.

In the accompanying drawing forming a part of this specification, and in which like numerals are employed to designate like parts throughout the same:

Figure 1 is a top plan view of one end of a conventional shuttle and bobbin, showing the improved retainer in association therewith and the face plate removed.

Figure 2 is a side view with portions shown in section to disclose more clearly the method of application of the retainer.

Figures 3 and 4 are transverse sections taken on the lines 3-3 and 4-4 respectively of Fig. 1.

Figure 5 is a detail perspective view of the improved retainer.

Figure 6 is a similar view with the connecting spring coils removed.

Referring to the drawing in detail, it will be observed that the reference character S designates one end of a conventional type of loom shuttle. As is usual, this shuttle is provided with an elongated recess R to accommodate a bobbin B. In the drawing, I have shown that type of bobbin which is provided with an enlarged corrugated head at one end and is additionally formed with an annular groove for reception of the grip-

ping jaws of the retainer. This type of bobbin requires no spindle. I wish it to be understood however, that while I have shown a particular type of bobbin, any other equivalent thread-carrier or wound package may be employed in connection with the present invention.

In order to supply the shuttle with my improved retainer clip, it is necessary to alter the latter slightly, and as will be observed from the drawing, the shuttle is formed in its upper and lower faces with elongated grooves 1 opening into the aforesaid recess R. These grooves are undercut as indicated at 2 to accommodate portions of the hereinafter described retainer. The shuttle is further countergrooved as at 3, leaving a relatively thin web 4 as a partition between the upper and lower counter-grooves.

Although the improved retainer could be constructed otherwise, it is preferably composed of two symmetrical half sections 5 which are substantially U-shaped in general outline. Each section comprises upper and lower attaching arms 6 which are bent as indicated at 7 to accommodate a portion of the head of the bobbin as seen more clearly in Fig. 1. The attaching arms 15 are bent together at their free ends as indicated at 8 and the extremities thereof are inturned as at 9.

The eight portions of the retainer sections are bent into arcuate formation as at 10 to provide opposed jaws for reception in the aforesaid grooves in the bobbin head. For the purpose of connecting the two wire sections together, I employ a pair of comparatively small coiled springs 11 which, as seen in Fig. 5, receive the inturned ends 30 of the sections. These springs 11 serve a very important additional function to appear later.

In order to secure the retainer in place, I preferably employ a pair of face plates 12 which are shaped to fit into the aforesaid elongated grooves 1. As seen more clearly from Fig. 2, these plates are provided with integral projections 13 on their inner faces which are adapted to be disposed in the aforesaid countergrooves 3. The projections and plates are formed with aligned holes, one of which is screw-threaded to receive the threaded end of a fastening screw or bolt 14.

It will be observed more clearly from Fig. 2 that the aforesaid springs 11 bear at one end against the projections 13. It is also to be noted that the so-called jaws 10 are spaced from the adjacent end of the recess R to permit a portion of the head of the bobbin to be disposed between said end and jaws. In this connection, it will be observed that the provision of the springs will permit the jaws to be moved towards and

from said end of the recess to accommodate different sized bobbins. It is in this way that the aforesaid self-adjusting connection is had. Attention is also directed to the fact that the face plates 12 do not bear on the arms of the retainer. Hence, these retainers are freely slidable against the tension of the springs. As before intimated, the springs serve the additional function of shock absorbers for the bobbin.

While the foregoing description will doubtless suffice to enable a clear understanding of the construction and method of application of the invention, it is deemed advisable to set forth in a more precise manner, the action of the important shock-absorbing means. To this end, it will be seen that as the springs are always under tension, they tend to maintain the head of the bobbin in very close spaced relation and sometimes in contact with the adjacent end of the recess of the shuttle. Referring to Fig. 1 and assuming that the shuttle has been struck by the picker stick to drive it in a direction from left to right, it will be seen that the spring means will maintain the bobbin in the aforesaid relation, and the shuttle and bobbin will move instantaneously as a unit, this being unobjectionable, as the bobbin then has no tendency to be driven out of the windings of thread. When the shuttle reaches the remote end of the guide-track and is checked by the other picker stick, it is obvious that the shuttle will move slightly with respect to the then inert bobbin, thereby absorbing the shock which would otherwise have a tendency to cause the endmost windings of thread to leave the other windings on the bobbin by momentum.

While the specific structure shown and described is the preferred embodiment of the invention, it is to be understood that changes in shape, size, and arrangement of parts may be resorted to within the scope of the adjoined claims.

I claim:

1. A device of the class described comprising a recessed shuttle, bobbin-embracing jaws in the recess thereof, and shock-absorbing means mounting said jaws within said recess.

2. A device of the class described comprising a recessed shuttle, relatively movable bobbin-embracing jaws in the recess thereof, and combined means for yieldably forcing said jaws toward each other and for yieldably mounting said jaws in the recess for slight movement longitudinally of the shuttle.

3. A device of the class described comprising a recessed shuttle, bobbin-embracing jaws in the recess thereof provided with carrying arms slidably engaged with said shuttle, and spring means connected with

said arms and engaged with a part of said shuttle for resisting the sliding movement of the jaws with respect to the shuttle.

4. A device of the class described comprising a recessed shuttle, a bobbin-retainer within said shuttle formed of two substantially U-shaped sections, the bight portions of said sections being shaped for reception in a groove in the head of a bobbin, the free end portions of said sections being slidably mounted in the bobbin, and coiled springs engaged with said free end portions of said sections to permit yielding thereof longitudinally of the shuttle.
5. A bobbin retainer comprising jaws for engaging the head of the bobbin, attaching arms for said jaws, and a coiled spring for connecting the ends of said attaching arms together.
6. A bobbin retainer formed from wire, said retainer comprising jaws for reception in the groove in the head of a bobbin, and a pair of attaching arms to slidably engage a portion of a shuttle, the extremities of

said attaching arms being inturned, and a coiled spring in which said inturned ends are received.

7. A bobbin retainer comprising a pair of substantially U-shaped sections, the bight portions of each section being shaped for reception in a groove in the head of a bobbin, the free end portions of the arms of said sections being bent together and the extremities being directed inwardly, and coiled springs for reception of said inwardly directed ends.

8. A bobbin retainer comprising jaws for engaging the head of a bobbin, and arms for attaching said jaws to a shuttle, a coiled spring for connecting said arms together, and a face for reception in a groove in a shuttle, said plate being provided with inwardly directed projections against which one end of the aforesaid spring bears.

In testimony whereof I have hereunto affixed my signature.

LOUIS ALEXANDRE CADORET.
